GLOWLAMP

Harry C. Jones, Los Angeles, Calif., assignor to
Ned Herbert Mann, Hollywood, Calif.

Application December 22, 1931, Serial No. 582,524

1 Claim. (Cl. 176—122)

This invention relates to improvements in glow lamps.

The general object of the invention is to provide a glow lamp including a cathode and an anode wherein the glow from the anode is concentrated and is arranged so that the concentrated glow is parallel to a casing covering the cathode and anode.

Another object of the invention is to provide an improved glow lamp including a transparent casing which has luminous gases therein and has a cathode and an anode therein with the anode in the form of a bar bent back upon itself in spaced relation in such a manner that the coronas from each leg of the anode meet intermediate the distance between the anode legs and form an intensified bar of light which is parallel to a portion of the transparent casing.

A further object of the invention is to provide a novel glow lamp comprising a transparent casing containing gases, a cathode, and an anode adapted to produce a glow which varies over a wide range of intensity with a small variation of the potential difference applied to the cathode and anode.

Other objects and the advantages of this invention will be apparent from the following description taken in connection with the accompanying drawing wherein:

Fig. 1 is a side elevation of my improved glow lamp.

Fig. 2 is a section taken on line 2—2 of Fig. 1.

Fig. 3 is an enlarged section taken on line 3—3 of Fig. 2.

Fig. 4 is a detail of the anode used in my improved device, and

Fig. 5 is a fragmentary section taken on line 5—5 of Fig. 3.

Referring to the drawing by reference characters, I have indicated my improved glow lamp generally at 10. As shown, the device 10 comprises a closed glass tube 12 mounted in a base 13 and secured thereto as by a suitable cement 14. The tube 12 is preferably made of pyrex or quartz glass and the base is made of a suitable insulating material such as hard rubber composition, "Bakelite" or some similar material.

Positioned in the tube 12 I provide an anode element 15 and a cathode element 16 both of which are preferably made of tantalum or any suitable metal.

The anode 15 is shown as in the shape of a round rod having a recess 17 therein in which is positioned a supporting wire 18 which is secured to the cathode by swaging as indicated at 19.

The wire 18 is preferably made of tungsten and is supported by a vacuum seal finger 20 which is integral with a hollow boss portion 21 of the tube 12.

The cathode 16 is in the shape of a flat bar bent back upon itself to form a pair of legs 22 with the curvature at the top as indicated at 23.

Adjacent the lower end the legs 22 are welded to a supporting wire 24 as at 25. The wire 24 like the wire 18 is preferably made of tungsten 10 and is supported by a vacuum seal finger 26 which is integral with the boss 21.

The anode 15 is spaced from the cathode 16, a distance which in this instance is shown as about one millimeter and the cathode is spaced from a portion of the side wall of the tube 12 a distance which is shown as approximately one eighth inch. Furthermore the cathode 16 is positioned parallel to the adjacent tube wall and the cathode is positioned parallel to the anode. 20

A wire 27 connects the anode wire 18 to a suitable plug contact 28 provided in the base 13 and a wire 29 connects the cathode wire 24 to a similar plug contact 30 provided in the base. The wires 27 and 29 are preferably made of Durmet 26 alloy and are shown as coiled around their respective coating wires 18 and 24 as at 31 and are welded thereto. The wires 27 and 29 may be secured to their respective plug contacts in any desired manner such as by soldering or welding. 30

Before the tube 12 is sealed it is evacuated and then filled with a gas mixture, preferably such as a mixture of neon and argon gases.

In operation the anode 15 is adapted to be connected through the medium of the contact plug 28 and the wires 27 and 18 to the positive side of a source of electrical energy and the cathode 16 is adapted to be connected through the medium of the contact plug 30 and the wires 29 and 24 to the negative side of the electrical potential. 35

When electrical current is delivered to the elements 15 and 16 a corona is formed around each of the legs 22 of the cathode 16 as indicated by the dotted lines 32 in Fig. 5. The distance between the legs 22 is such that the coronas from the legs meet intermediate the distance between the legs and form a concentrated light glow in the form of a thin bar parallel to the legs 22. In certain instances of operation, as the normal applied potential is decreased the glows 32 about the legs 22 recede so that the two glows fail to meet and no concentrated light glow is formed. Upon further reduction of potential all glow about the cathode 16 will cease. When the normal poten- 45 50 55

tial is exceeded the region of tube between the legs 22 will glow with increased brilliancy. In this manner small variations of the applied potential will cause wide variations of the light intensity. With the portion of the tube 12 adjacent the cathode 16 parallel with the cathode the light glow thus formed between the legs of the anode passes through the tube 12 in practically a thin straight line as indicated by the dotted line 33 in Fig. 5. By arranging the portion of the tube 12 which is adjacent the elements 15 and 16 parallel to the elements and also parallel to the combined glow 33 caused by these elements, the refractive and dispersive effect of the tubing is reduced to a minimum allowing the glow to be

focused more accurately and allowing certain portions of the glow to be selected for focussing.

From the foregoing description it will be apparent that I have provided an improved glow lamp which is of novel construction and is highly efficient in use.

Having thus described my invention, I claim:

In a glow lamp a hollow closed transparent member, a cathode in said member, said cathode comprising a flat strip of material bent to U-shape to provide two spaced leg portions, and an anode, said anode comprising a straight elongated member cylindrical in cross-section and arranged parallel to and equidistant from the leg portions of the cathode member.

HARRY C. JONES.
